UNITED STATES PATENT OFFICE.

FRED FRAZER, OF SYRACUSE, NEW YORK.

DESIGN FOR A HAME-TOP.

SPECIFICATION forming part of Design No. 17,026, dated December 21, 1886.

Application filed November 13, 1886. Serial No. 218,837. Term of patent 14 years.

To all whom it may concern:

Be it known that I, FRED FRAZER, a citizen of the United States, residing at Syracuse, in the county of Onondaga and State of New York, have invented and produced a new and original Design for Hame-Tops, of which the following is a specification, reference being had to the accompanying drawing, forming a part thereof.

10 The said drawing illustrates in perspective a portion of a hame with my newly-designed top shown in connection therewith.

15 The leading feature of my design consists of a hame-top of a suitable curvature having the dome-shaped configuration, which I will now proceed to describe.

20 A indicates the top portion of my design for a hame-top, which is convex or dome-shaped, running to an edge, a , which forms the base of the said convex portion. From the rim a the top is formed with an elongated concave de-

25 pression, a' , which gradually decreases in di-
ametric cross-section, terminating in another circular edge, a^2 , and from thence extending down to the body of the hame B in a short bevel, a^3 , slightly convex in form. At the point a^4 the elongated concave depression a' is of the shortest cross-sectional diameter, extending slightly outward to the edge a^2 , and making a short outward graceful sweep up to 30 the edge a . The top is of circular form.

I claim—

The design for a hame-top herein shown and described, the same consisting of a circular convex or dome-shaped top, A, terminating in 35 edge a , a slightly-elongated concave portion, a' , forming an indentation from the edge a to the edge a^2 , and a short bevel, a^3 , extending from the edge a^2 to the body of the hame and terminating the top.

FRED FRAZER.
